CARBON HOLDING DEVICE

Frank Iacobelli, West Haven, and Victor Cassella,
Hamden, Conn., assignors to Harry Granville,
Jr., Scranton, Pa.

Application March 23, 1937, Serial No. 132,550

2 Claims. (Cl. 176—119)

This invention relates to carbon holding devices for use in arc light mechanisms and more particularly to a carbon holder for use with motion picture projecting machines.

5 The device of this invention is especially adapted to save carbons used in arc light machines wherein at least one of the carbons is fed toward the other to maintain the arc therebetween and to compensate for the using up of the 10 carbon when in operation. In such machines, and particularly in motion picture projectors, the carbons are disposed horizontally, and provision is made of a carbon guiding support for the end of the carbon, which guide is disposed adjacent 15 the opposing carbon ends.

One of the objects of this invention is to provide an improved carbon holding device whereby the carbons of arc lights may be used until they are of minimum length and whereby the expense 20 of carbon replacements will therefore be reduced to a minimum.

Another object is to provide a carbon holder adapted to clamp a short length at one end of the carbon, to be held in turn in the carbon carrier of an arc light mechanism, and which will readily move past the carbon guiding support, without interfering with the carbon guiding action thereof and thereby permit the use of a maximum length of the carbon.

30 A further object of this invention is to provide a carbon holding device of the above nature which will be relatively simple in construction, inexpensive to manufacture, readily associated with standard arc light mechanisms, compact, ornamental in appearance, and very efficient, convenient, practical, and durable in use.

With the foregoing and other objects in view, which will appear as the description proceeds, the invention resides in the combination and arrangement of parts, and in the details of construction hereinafter described and claimed.

A preferred embodiment of the invention is illustrated in the accompanying drawing, wherein:

45 Figure 1 is side view of certain parts of an arc light mechanism used in one type of movie film projector and showing a carbon holding device, embodying the features and principles of this invention, associated therewith;

50 Figure 2 is an enlarged end view of the negative carbon, its support, and the holder of this invention, looking in the direction of arrows 2—2 in Figure 1;

Figure 3 is an enlarged side view of the carbon holding device of this invention; and

Figure 4 is a section taken on line 4—4 of Figure 3.

Referring to the drawing wherein like reference characters designate like parts throughout the several views, and with particular reference 5 to Figure 1, 10 indicates a reflector, through which a negative carbon carrier 11 is adapted to slide to feed the carbon 12 toward the positive carbon 13. The carbon 12 is supported adjacent its forward end, being used to create an arc between it and the carbon 13, upon a stationary guiding support 14. The support 14, in order to properly support and guide the carbon 12 as it is being fed by the carrier 11, is provided with a groove 15, see Figure 2, which has a surface contour fitting the surface contour of the carbon guided thereby. Herein the carbon 12 is shown as being cylindrical in form, and therefore the groove 15 is semi-circular in cross-section and of a diameter substantially equal to the diameter 10 of the carbon. The positive carbon 13 is likewise 15 fed by a carrier 16 and is supported at its forward end by a stationary guiding support 17 having a groove 18 therein, the contour of which fits 20 the contour of the carbon 13.

25 In accordance with the features and principles of this invention a carbon holding device 20 is associated in combination with the above described parts, to obtain the desired results and advantages contemplated, among which are those 30 referred to above. The holder 20 is provided with an elongated shank 21 which is contoured to fit an opening 22 provided in the carriers 11 and 16, and in which the carbons are usually clamped. The shank 21 extends rearwardly from 35 a body portion or jaw 23 which is bored out at its forward end in alignment with the shank 21 to provide a socket 24 to fit and partially embrace the carbon to be used therewith.

40 Preferably the width of the body portion or jaw 23 is substantially equal to the diameter of the carbon 12 or 13. The socket 24 is preferably not less than one inch deep and has a flat bottom 25 against which the end of the respective carbon will seat. The lower surface 26 of the body 45 portion 23 is formed or curved to coincide with the form or curvature of the carbon. As shown, the socket 24 has no lower wall, it having been removed when the socket was formed, due to the diameters of the socket and the carbon being 50 equal to each other, and to the width of the body portion. Due to this construction the lower surface of the holder 20 will also fit the contour of the grooves 15 or 18 in the support 14 or 17 and the carbons 12 or 13 will be continuously under 55

the guiding influence of the guides 14 and 17 even after their rear, or held, ends have moved past these guides.

The carbons 12 and 13 are clamped in their respective holders 20 by the forward end 27 of a clamping finger or jaw 28, which has its rear end 29 disposed in a longitudinally directed slot 30, provided in the curved lower surface 26 of the body portion 23. A lug 31 extends upwardly from 10 the finger 28 into the slot 30 intermediate the rear end 29 and the forward end 27. A pin 32 is passed through the body portion 23 and the lug 31, whereby the finger 28 is pivoted to the body portion 23 and may be swung to clamp 15 the carbon end, disposed in the socket 24, to said body portion. A screw 33 threadingly associated with a threaded opening 34 directed downwardly through the body portion 23 and into the slot 30, engages the rear end 29 of the finger 28 to 20 swing it into clamping engagement with the carbon disposed in the socket 24.

The finger 28 is formed relatively narrow in thickness, see Figures 2 and 4, and extends below the lower surface of the shank 21, and of the 25 carbons 12 and 13. Provision of a recess 35 in the bottom of the grooves 15 and 18 in the respective supports or guides 14 and 17, see Figure 2, permits the holders 20 to pass by the guides 14 and 17, while the respective carbon and its holder 30 are supported in the grooves to maintain the carbons 12 and 13 in their desired opposed parallel positions which, in most instances, is with the axis of the positive carbon 13 slightly above, but parallel with, the axis of the negative carbon 35 12.

When in use, in cooperating association with an arc light mechanism including the carriers 11 and 16 and the respective guiding supports 14 and 17, the holders 20, extending as they do 40 beyond the carriers 11 and 16, replace a considerable length of carbon which is usually wasted when such holders are not used. By being adapted to be fed past the guiding supports 14 and 17, while still maintaining the carbon in the desired 45 operable position, the holders 20 further save carbon, by permitting the use of the carbons up to a point closely adjacent the forward ends of the holders 20. The form of the finger 28 whereby it may slide through a narrow slot 35 provided 50 in the guiding supports 14 and 17, obviates any interference of this part with the free sliding of the carbons and the rear end of the holders 20, upon the guiding surfaces formed by the grooves 15 and 18. The carbons 12 and 13 are not only 55 firmly clamped in the holders 20 by the fingers 28 but due to the extent of the contact of the

carbon end with the surface of the socket 24 an efficient electrical connection therebetween is established and maintained. The sturdy construction of the holders 20, particularly the portion 23 adjacent the arc end of the carbons, insures 5 durability against rapid burning by the arc.

While there has been disclosed in this specification a form in which the invention may be embodied, it is to be understood that this form is shown for the purpose of illustration only, and that the invention is not to be limited to the specific disclosure, but may be modified and embodied in various other forms without departing from its spirit and that the invention includes all the modifications and embodiments coming within the scope of the following claims.

Having thus fully described the invention, what is claimed as new, and for which it is desired to secure Letters Patent, is:

1. A carbon saver for carbon electrodes of the character used with motion picture projectors comprising, a stationary carbon support along which a carbon may be fed, said support having a groove to fit the contour of a carbon and a narrow slot extending below the surface of the 24 groove, a carbon holder having a body portion formed with an extension adapted to be clamped in an electrode holder of a projection lamp, the body portion of said holder being formed to fit the contour of groove in the carbon support 30 whereby the holder will move freely therethrough, a narrow swingable jaw portion extending below said body and adapted to move through the slot in the stationary support and means to swing said jaw to clamp a carbon between it and the body 35 portion of the holder.

2. A carbon saver for carbon electrodes of the character used with motion picture projectors comprising, a stationary carbon support along which a carbon may be fed, said support having 40 a groove to fit the contour of a carbon and a slot extending below the surface of the groove, a first jaw adapted to partially embrace an end of a carbon, said jaw having a narrow slot formed therein and extending longitudinally thereof, a 45 narrow second jaw disposed in said slot, extending forwardly below the carbon embracing portion of the first jaw and adapted to move through the slot in the stationary support, means to pivotally connect said jaws and screw means threadingly cooperating with one jaw and engaging the other to move said second jaw relatively to the first to clamp a carbon therebetween.
